UNITED STATES PATENT OFFICE

DAVID W. RUBIDGE, OF PITTSFIELD, MASSACHUSETTS, ASSIGNOR, BY MESNE ASSIGNMENTS, TO UNDERWOOD ELLIOTT FISHER COMPANY, A CORPORATION OF DELAWARE

TYPEWRITING MACHINE

Application filed November 14, 1929. Serial No. 407,251.

My invention relates to typewriting machines, more particularly to typewriting machines intended to write upon a number of superposed continuous work-sheets or webs, 5 and has for its object the provision of an improved typewriting machine of this character.

My invention is especially related to typewriting machines provided to write upon superposed continuous sheets or webs which are intended to be torn off in sections from the body of the web so that each section when the typewriting thereon has been completed may be detached or removed. It is the usual 15 practice to employ carbon sheets interleaved with the work-sheets or webs for making the duplicate copies.

Heretofore in practice, these carbon sheets were only long enough to cover the form sections of the work-sheets. When the typewriting on one work section had been completed, it was necessary to remove the carbon sheets individually free from the completed work section and then interleave them with 25 the plies of the succeeding section. This operation of removing the carbon sheets from the plies of the completed section and of interleaving them with those of the succeeding section required a considerable amount of 30 time.

In an endeavor to overcome this difficulty, carbon carriers were provided and arranged to draw the carbon sheets back along the work-sheet web so that upon the completion of 35 one work section, the carbon webs could be interleaved with the plies of the succeeding work section without their being removed from the plies of the work-sheet. This arrangement eliminated the necessity of removing the carbon sheets individually from the completed work section and of assembling them individually with the succeeding section. This remained true as long as the carbon sheets were fresh but upon their becoming 40 worn it was necessary as before to remove them individually and to substitute new sheets.

Moreover, this practice proved to be expensive in that when it became necessary to assemble new sheets, it was customary to pro-

vide a complete fresh set in spite of the fact that often-times but a portion of the total number of sheets needed replacement. Thus, where both hectograph and carbon sheets were being used, the wearing ability of the hectograph, which is much inferior to that of the carbon sheet, determined the time at which new sheets were to be provided. Also, this practice proved to be a very expensive one because it was possible to use only but a portion of the carbon areas.

An effort was made to utilize substantially the entire carbon areas of the sheets by reversing the sheets in the work-sheet sections, but this resort did not prove entirely satisfactory because the operation involved considerable effort and time.

Thus, the aforescribed arrangement possessed certain disadvantages inherent in the former practice in that it was necessary frequently to interleave fresh carbon sheets with the work-sheet web; the replacement, as before being determined by the quality of the poorest wearing sheet.

In carrying my invention into effect in one form thereof, I provide a carbon carrier to support rolls from which continuous sheets of carbon may be drawn. It will be understood that several continuous sheets of carbon may be wound on one roll and that several like rolls may be used. The number of sheets used and the number of rolls employed will depend upon the number of work-sheets being fed to the platen of the machine and upon the kinds of carbon used. Preferably, the carbon rolls will be mounted on the carbon carrier to the side of the line of movement of the work-sheets to the platen. I provide suitable means for separating the carbon sheets withdrawn from the rolls and for guiding them crosswise of the line of movement of the work-sheets for interleavement with the work-sheets. Moreover, I provide suitable guiding means on the carbon carrier for directing the carbon sheets into the line of movement of the work-sheets. In order to facilitate the interleavement of the carbon sheets with the plies of the work-sheet web, I movably secure the latter guiding means on the carrier so that the guiding means for

each sheet may be readily moved from its working position to a remote position. The operator is thereby enabled to readily assemble each carbon sheet with its guiding means 5 and to readily interleave the sheet with its respective work-sheets.

Suitable locking means are provided for each roll so that accidental unwinding of the carbon sheets will be prevented and so that 10 the rolls may be released to permit the withdrawal of the carbon sheets for interleaving and renewal purposes.

For a more complete understanding of my invention reference may be had to the accompanying drawings in which Fig. 1 is a perspective view illustrating a typewriting machine embodying my invention; Fig. 2 is a front elevation of the carbon carrier provided for the typewriting machine of Fig. 1; Fig. 20 3 is a side elevation of a portion of the typewriting machine; Fig. 4 is a perspective view of a portion of the carbon carrier illustrating certain structural details; Fig. 5 is a fragmentary view illustrating certain structural 25 details; Fig. 6 is a fragmentary view illustrating certain structural details; and Figs. 7, 8, 9 and 10 are diagrammatic views illustrating the manner in which the carbon sheets are interleaved with the plies of the work- 30 sheet web.

Referring to the drawings, I have shown my invention in one form in connection with a typewriting machine intended to write upon superposed work-sheets or webs 35 which are arranged in sections so that when the writing upon a section has been completed, it may be torn off or detached from the body of the web. As shown, the typewriting machine comprises a framework 40 upon which the usual platen (not shown), and a carbon carrier table 11, over which the work-sheet web 12 is passed to the platen, are mounted. The platen is provided with the usual hand wheel 13 which is mechanically 45 connected with the platen.

It will be understood that the platen will be journaled in a suitable frame which comprises side plates 14. These plates in turn are pivoted at 15 so that the platen may be 50 swung up and down between its operative position and a web releasing position. The frame provided to thus support the platen may be locked with the platen in its operative 55 position by means of suitable hook arms 16 arranged to engage cooperating pins (not shown) mounted on the platen frame.

The platen carriage carries a front paper table 17 over which the leading form sections 60 of the work-sheet web 12 are passed. This table is provided with the usual gauge arm 19 which together with the front table serves to support and guide the advancing end of the work-sheet web. The usual gauge 20 is 65 provided on the gauge arm for determining

the length of the work-sheet sections to be severed.

It will also be understood that the platen carriage will be provided with a rear paper table and apron (not shown) for guiding the web and carbons down around and in the front of the platen. In operation, the work-sheet web 12 is led from the carbon carrier table 11 over the rear apron and table around the platen and up over the front table 17. 75 The platen carriage is supported on the machine frame 10 for letter feed and return directions by means of the usual rail 23.

The carbon carrier table 11 over which the work-sheet web 12 is passed to the platen from the rear of the machine is mounted on the machine frame for movement with the platen carriage in letter feed and return directions. As shown, this table is a substantially rectangular framework comprising a pair of substantially parallel side bars 24 which are interconnected at their rear by means of an end bar 25 and at their front by means of a bar 26. Preferably although not necessarily so, these bars will be formed integrally into the rectangular frame. The table is supported at its rear on a rail 27, which is mounted on the frame 10, by means of a pair of rollers 28, and is supported at its front by means of a pair of lugs 30 secured to the platen carriage. 80 It will be observed (Figs. 1 and 3) that each end of the front bar 26 is provided with a reduced axially extending portion 26a which is received in an apertured upright portion 30a provided on the associated lug 30. The front end of the table, therefore, is rigidly secured to the platen carriage so as to be supported thereby and also so that the letter feed and return motions of the carriage will be imparted to the table. Preferably, the rear end of the table will be secured against vertical motion, by means of a pair of L-shaped clips 31, each of which is secured to the table so that its horizontal arm projects 85 beneath the rail 27. 90

It will be understood that the plies of the work-sheet web 12, which is fed to the platen over the table 11 from the rear of the machine, will be interleaved with carbon sheets so that a plurality of duplicate copies will be produced simultaneously with the production of the first copy of the work. 100

As has been pointed out, one of the features of my invention is the provision of means for carrying rolls of continuous carbon sheets on the carbon carrier table 11 and further, the provision of means for guiding the carbon sheets into their respective plies of the work-sheet web, the arrangement being such that it is unnecessary to remove the carbon sheets separately from the completed section of the work-sheet in order to assemble them with the succeeding section. Moreover, the arrangement is such that the worn portions of individual carbon sheets may be removed or de- 105 110 115 120 125 130

tached without disturbing the assembly of the remaining sheets.

As shown, I have provided a suitable carbon carrier 35 mounted upon the carbon table 11 and arranged for movement toward and away from the platen in the line of movement of the work-sheet web 12. The carbon carrier 35 comprises spools provided to support rolls 36 of superposed continuous carbon sheets 37, 10 plate-like roll supports 38 and a suitable supporting carriage 39. The spools 36a (Fig. 6) for the carbon rolls are each provided with a pair of spool-ends 36b. The spool ends are provided with projecting stud-like rods or 15 pins 36c which serve to rotatably mount the rolls within U-shaped receiving and retaining grooves 38a provided in the plate-like supports. Preferably, the rolls will be mounted on axes substantially parallel with the line 20 of movement of the work-sheet web 12 to the platen. It will be understood, of course, that the plates 38 may be provided with a number of sets of these U-shaped grooves for receiving a corresponding number of rolls.

25 The carriage 39 has a substantially rectangular supporting frame 40 (Fig. 4) which is arranged to receive and support a frame 41. The frame 41 serves to mount the roll supports 38, which as shown are secured in pairs 30 to the opposite end portions of cross members 42. Each support 38 is provided at its lower edge with an inturned ear or lug 38b which in the assembled carrier is suitably secured to the cross-member. Each member 42 35 is suitably secured to the upper rectangular frame 41 by means of an intermediate plate 43 (Fig. 4), which is secured in cantilever fashion to the frame 41, suitable screw fastening means 44 serving to secure these members 40 together. The plates 43 may be adjusted to 40 various positions upon the frame 41 so as to accommodate work-sheet webs having different widths.

45 The lower supporting frame 40 is mounted for movement toward and away from the platen upon a pair of guide and supporting rails 45 suitably secured as by means of the screw fastening means 46 (Fig. 4) to the parallel side bars 24 of the table 11. As 50 shown, the frame 40 is provided with a pair of rollers 47 on each side, these rollers being shaped to receive the edges of the associated rails 45 to thereby support and guide the carbon carrier.

55 Preferably, the upper frame 41 will be detachably secured to the lower supporting frame 40 so that the upper frame together with the rolls and their supports may be readily removed from the machine. As 60 shown (Figs. 2 and 4), the upper frame is provided with depending lugs 48 which are arranged when the upper frame rests upon the lower frame to be received in corresponding apertures 49 provided in the lower 65 frame. Each lug 48 is provided with a

notch or recess 48a which is arranged in the assembled table to receive a latch member 50 pivoted to the lower frame 40. It will be understood that when the latches are moved so as to be received by the corresponding recesses 48a, the frame 41 will be locked in place upon the frame 40. To remove the frame 41 from the machine, it is simply necessary to move the latches 50 to their releasing positions and lift the frame 41 from the frame 40. 75

It will be observed that each carbon roll is mounted within its spaced supports 38 on an axis substantially parallel with the line of movement of the work-sheet web and the carbon carrier so that the carbon sheets as they are withdrawn from the spool for interleaving with the plies of the work-sheet web will be led transversely over the carbon carrier. It will be understood, therefore, that since the carbon sheets are led over the carbon carrier at right angles to the line of feed of the work-sheet web, it is necessary to turn the carbon sheets at right angles so that when interleaved with the plies of the work-sheet web, the interleaved carbon sheets will move toward the platen together with the web. 80 85

In order to thus turn the carbon sheets withdrawn from the rolls into the line of movement of the work-sheet web, I provide a series of turning rods 51, one rod for each carbon sheet withdrawn. As shown, each rod has an angular shape and is mounted in the roll supports 38 so that when it is in its working position, a portion 51a of the rod will be positioned diagonally across the crosswise path of movement of the carbon sheet withdrawn from the roll so that if the carbon sheet withdrawn from the roll be turned about the diagonal bar, it will be directed into the line of movement of the work-sheet web. 90 95 100 105

Each rod 51 is pivotally mounted in the supports 38 provided for the carbon rolls from which the associated carbon sheet is withdrawn, and preferably so that its pivotal axis will be parallel with the axis of the roll. For this purpose the ends of the angular rod 51 are provided with projecting portions 51b which in the assembled carrier are received by suitable apertures provided in the supports 38. The rods will be formed from a resilient material such as phosphor-bronze or spring steel so that the rods may be sprung into position between the supports 38 and be secured thereto with the projecting portions 51b received in their associated apertures by the inherent resiliency of the rod. Preferably one of the projecting portions 51b will be provided with a recess or notch 51c, the end portion of the projection beyond the notch being formed at an angle with the main portion or the projection (Fig. 5). The recess and bent end portion are arranged so 110 115 120 125 130

that when the rod is positioned in the plates 38, the outer edge of the recess will engage the outer side of its associated plate 38 (Fig. 5). It will be observed that by reason of this construction the rods will be securely locked in their supporting plates. In order to remove the rod, it is necessary to move the unnotched end of the rod inward from its plate 38 (Fig. 5) and then draw it toward the right so that the bent end portion of the recessed end may be withdrawn from its aperture. The path assumed by the unnotched projecting end of the rod during this operation is clearly shown by the arrow in Fig. 5.

It is desirable to separate the superposed carbon sheets as they are withdrawn from each roll and to guide them to their respective work sheet plies without fouling. For this purpose, I have interposed between the rolls and the path of travel of the work-sheet web a plurality of vertically spaced rod-like members 52. It will be understood that these rods will be suitably spaced and that each carbon sheet withdrawn will be passed over (or under) its rod so as to be directed substantially into the plane passed between the work-sheets with which it is to be interleaved. Thus, the carbon sheets will be guided to their respective sheets without fouling.

It will be understood that during the line feed movement of the platen, the carbon sheets are not withdrawn from the carbon rolls and that during this movement the carbon carrier will be drawn toward the platen with the work-sheet web, and it will also be understood, of course, that a sufficient length of the carbon sheets will have been withdrawn to form the multiple copies. It is desirable, therefore, in order to prevent accidental unwinding of the carbon rolls to provide positive locking means for each roll. For this purpose, I have provided for each spool a suitable locking pin 53 which is mounted on one of the roll supports adjacent one of the spool-ends by means of a supporting strip 53a. This strip will be formed from a suitable resilient material such as phosphor-bronze. As shown, the support 38 is provided with an aperture for each pin and through which the pin projects so as to engage the spool-end. Preferably and as shown (Figs. 2 and 6), the spool-end will be provided with a plurality of apertures 54 arranged in a circle adjacent the periphery of the head and the locking pin 53 will be positioned so that when its end will be projected into one of the apertures. To release the roll it is but necessary to withdraw the pin from the aperture. This arrangement provides means for positively locking the carbon roll in any desired position and for effecting a ready release of the roll.

It is preferable to guide the work-sheet

web together with the interleaved carbon sheets from the rear of the machine to the platen. As shown, I provide a pair of guides 55 for the edges of the work-sheet web at the rear of the machine and a similar pair of guides 56 for the edges of the work-sheet web and the carbon sheets at the front of the machine.

The pivotal mounting of the guide rods 51 is a very important feature of my invention in that by reason of this construction it is possible for the operator with but little effort to quickly interleave the carbon sheets with the plies of the work-sheet web.

The operation of interleaving the carbon sheets with their respective work-sheet plies will be readily understood by reference to Figs. 7-10 inclusive. In these figures but three plies of the work-sheet web 12 have been shown and accordingly but two carbon sheets with their associated rolls have been shown. It will be understood, of course, that the number of carbon sheets will be one less than the number of plies and furthermore that each roll of carbon may consist of superposed carbon sheets.

In order to interleave the carbon sheets with the web plies, the lower carbon sheet, that is the sheet shown at the right of Fig. 7, is drawn from the spool crosswise of the carbon carrier under (in this case) its guiding and separating bar 52. The spools, of course, will be unlocked during the interleaving operation. Then with the guide rods 51 for the upper carbon sheets swung upwardly (Fig. 7) from their working positions, the lower carbon length is turned around and brought forward under its guide rod 51 to a position slightly forward of the carbon carrier (Fig. 9). The arrows shown in Fig. 8 will make clear the path assumed by the carbon sheet during this operation. It will be understood that the guide rod 51 may be rotated about its axis to any suitable position most convenient for the carbon turning operation.

In like manner the carbon sheet for the next higher ply will be withdrawn from its spool, passed under (or over) its guide bar 52 in order to bring it into a plane substantially that of its corresponding work-sheet ply, and then turned about its diagonal guide bar 51.

After the carbon sheets have thus been withdrawn and turned about their guide rods 51 and with these rods in their respective positions shown in Fig. 8, the work-sheet web is drawn forward to a position slightly forward of the carbon carrier (Fig. 9). Then the upper sheets of the web are raised so that the lower guide rod 51, together with the carbon sheet turned about it, may be moved downwardly to bring the carbon sheet into the plane of the lower work-sheet (Fig. 9). The upper ply is then lowered and the

next upper guide rod with its carbon sheet is positioned between the upper work-sheets (Fig. 10).

Likewise if there be more work-sheet plies, 5 successively higher carbon sheets will be turned about their guide rods and be interleaved with their respective plies.

If the first fold of the web section is at the right rather than the left, as viewed in Figs.

10 7-10, the carbon carrier assembly will be detached from the carrier frame 40 and will be rotated through 180° horizontally and replaced on the carrier frame. The guide rods 51 will then be reversed so as to be positioned 15 correctly to turn the carbon webs toward the platen. It will be understood that by thus reversing the roll carrier, the lower guide rods 51 and 52 will be transferred from the left to the right side.

20 After the carbon sheets have been interleaved with the work-sheet web, the web together with the interleaved carbon sheets will be drawn forward to the platen and into position for printing on the leading web section.

25 The carbon rolls will then be locked. Preferably, the work-sheet web during the interleaving operation will have been drawn to a position slightly in advance of the carbon sheets (Figs. 9 and 10) so that after the typ-

30 ing of the first work-sheet section has been completed, the leading ends of the section may be pinched together without pinching the carbons. With the work-sheets thus pinched together, and secured, the carbon car-

35 rier may be withdrawn rearwardly to its initial position, whereby the carbon sheets will be withdrawn from the completed work section and will be interleaved with the succeeding section. This same result may be

40 obtained by moving the leading ends of the work-sheets and carbon sheets to the same position in advance of the carbon carrier during the interleaving operation and then after the web together with the carbon sheets has

45 been moved forward into the printing position and with the carbon spools locked, giving the carbon carrier a rearward throw sufficient to draw the leading ends of the carbon sheets slightly rearward of the leading ends 50 of the work-sheet web.

It will be understood, therefore, that the carbon sheets may be withdrawn from the completed work section merely by holding the leading edges of the completed section 55 and then pushing the carbon carrier rearward to its initial position.

When it is desired to replace worn carbon areas with fresh printing surfaces it is only necessary to unlock the carbon rolls, draw 60 the carbon sheets forward a distance sufficient to provide the fresh surfaces, and then tear off or detach the leading carbon portion. It will be understood that it is not necessary to tear off a carbon length equivalent to the 65 length of a work-sheet section in order to pro-

vide fresh carbon areas. Thus, often-times the work-sheet form will be such that it is merely necessary to tear off but a very small portion of the carbon sheet in order to move fresh carbon areas beneath the forms to be printed. This method of supplying fresh carbon areas obviously contributes to an economy of material.

The arrangement of the carbon rolls is also of advantage when carbons having different 70 wearing qualities are being used because it is possible to withdraw any portion of the worn sheets without disturbing the remaining unworn sheets. Thus for example, when hectograph sheets are being used these sheets may be wound into separate rolls so that when portions of the hectograph become worn the hectograph rolls alone may be unlocked to permit the worn portions to be detached.

It is to be noted that the carbon carrier and the associated guide members have a comparatively strong construction and yet the construction is very light. The frames 40 and 41 and likewise the supports 38 are of light plate-like form, while the guiding means 90 51 and 52 have a light rod-like form.

What I claim as new and desire to secure by Letters Patent of the United States is:

1. The combination with a typewriting machine having a platen of means for guiding superposed work-sheets to said platen, a carbon carrier mounted on said machine for movement toward and away from said platen, means for supporting continuous carbon sheets on said carrier, means for directing said carbon sheets crosswise of the line of movement of said carbon carrier for interleavement with said work-sheets, guiding means for directing the carbon sheets into the line of movement of said work-sheets, and means for movably securing said guiding means so that they may readily be moved from their working positions to facilitate the interleavement of said carbon sheets with said work-sheets.

2. The combination with a typewriting machine having a platen of means for guiding a multiple-ply work-sheet web to said platen, a carbon carrier mounted on said machine for movement toward and away from said platen, means for directing superposed carbon sheets crosswise of the line of movement of said carbon carrier and for separating the superposed sheets for interleavement with the plies of said work-sheet web, a guide member for each carbon sheet having a rod which when the member is in its working position is interleaved with a ply of said work-sheet web and is placed diagonally 125 across the cross-wise line of movement of the corresponding carbon sheet and about which the sheet is turned so as to be directed into the line of movement of said work-sheet web and means for movably mounting said guide 130

members on said carbon carrier so that they may be moved from their working positions to remote positions to facilitate the interleaving of the carbon sheets and their corresponding guides with the plies of said work-sheet web.

3. The combination with a typewriting machine having a platen of a carbon carrier on said machine for movement toward and away from said platen, means for directing a carbon sheet in said carbon carrier crosswise of the path of movement of said carbon carrier and a diagonally positioned pivotally mounted bar on said carbon carrier for directing the carbon sheet toward said platen.

4. The combination with a typewriting machine having a platen of a carbon carrier on said machine for movement toward and away from said platen, means for directing a carbon sheet in said carbon carrier crosswise of the path of movement of said carbon carrier, a diagonally positioned bar for directing the carbon sheet toward said platen, means on said carbon carrier for pivotally mounting said bar and means for locking said bar in its pivotal mounting.

5. The combination with a typewriting machine having a platen of means for guiding work-sheets to said platen, a carbon carrier mounted on said machine for movement toward and away from said platen, guiding means for directing a carbon sheet on said carrier crosswise of the line of movement of said carrier for interleavement with said work-sheets and means for directing said carbon sheet into the line of movement of said work-sheets comprising a resilient angle member having a diagonally positioned bar for turning said carbon sheet toward said platen and supporting means on said carbon carrier for receiving the end portions of said angle member so that said member is pivotally mounted on said carrier and is secured by its inherent resiliency.

45. 6. The combination with a typewriting machine having a platen of a table, means for guiding a fanfold work-sheet web to said platen, a carbon carrier mounted for movement on said table toward and away from said platen in the line of movement of said work-sheet web, means for directing carbon sheets on said carbon carrier crosswise of the path of movement of said carrier so as to be interleaved with the plies of said fanfold work-sheet web, and means for directing each carbon sheet toward said platen comprising an angle shaped rod having one side positioned diagonally to turn said carbon sheet toward the platen and means for pivotally mounting said rod at its end portions on an axis substantially parallel with the line of movement of said carrier.

7. The combination with a typewriting machine having a platen of means for guid-

ing a fanfold work-sheet web to said platen, a carbon carrier mounted on said machine for movement toward and away from said platen in the line of travel of said work-sheet web, means for directing superposed carbon sheets on said carrier crosswise of the line of movement of said carrier and for separating the sheets for interleavement with the plies of said fanfold work-sheet web, said means comprising supports on said carrier positioned on opposite sides of the path of travel of said carbon sheets and a plurality of vertically spaced rods mounted on said supports and about each of which one of said carbon sheets is passed, and pivotally mounted members on said carbon carrier arranged to turn and direct the carbon sheets along the line of travel of said work-sheet web.

8. The combination with a typewriting machine having a platen of means for guiding a fanfold work-sheet web to said platen, a carbon carrier mounted on said machine for movement toward and away from said platen in the line of travel of said work-sheet web, means for directing carbon sheets on said carrier crosswise of the line of movement of said carrier for interleavement with the plies of said fanfold work-sheet web, and means on said carbon carrier for turning said carbon sheets along the line of travel of said work-sheet web, said means comprising supports positioned on opposite sides of the path of travel of said carbon sheets and an angle shaped rod for each sheet pivotally mounted on said supports so that one portion of said rod with the rod in its working position is positioned diagonally across the line of travel of said carbon sheet and about which said sheet is passed so that it is turned into the line of travel of said work-sheet webs.

9. The combination with a typewriting machine having a platen of means for guiding a fanfold work-sheet web to said platen, a carbon carrier mounted on said machine for movement toward and away from said platen in the line of travel of said work-sheet web, means for directing carbon sheets on said carrier crosswise of the line of movement of said carrier and for separating the sheets for interleavement with the plies of said fanfold work-sheet web, said means comprising supports on said carrier positioned on opposite sides of the path of travel of said carbon sheets and a plurality of vertically spaced rods mounted on said supports and about each of which one of said carbon sheets is passed, and means for turning and directing the carbon sheets along the line of travel of said work-sheet web, said means comprising an angle-shaped rod for each sheet pivotally mounted on said supports, one portion of said rod with the rod in its working position being positioned diagonally across the line of travel of said carbon sheet and about which

said sheet is passed so that it is turned into the line of travel of said work-sheet webs.

10. The combination with a typewriting machine having a platen of means for guiding a fanfold work-sheet web to said platen, a carbon carrier mounted on said machine for movement toward and away from said platen in the line of travel of said work-sheet web, a rotary spool for holding superposed carbon sheets provided to be interleaved with the plies of said work-sheet web, a pair of supports on said carrier for rotatably mounting said spool with its axis substantially parallel with the line of travel of said work-sheet web, a pin mounted on one of said supports operably associated with one of the spool-ends for locking the spool against rotation and for releasing it to permit the withdrawal of the carbon sheets from said spool, means for directing said carbon sheets thus withdrawn crosswise of the line of travel of said carrier and for separating them for interleaving with the plies of said fanfold work-sheet web, said means comprising a plurality of vertically spaced rods mounted on said supports and about each of which one of said carbon sheets is passed, and means for turning and directing the carbon sheets along the line of travel of said work-sheet webs, said means comprising an angle-shaped rod for each carbon sheet pivotally mounted on said supports, one portion of said rod with the rod in its working position being positioned diagonally across the line of travel of said carbon sheet and about which the sheet is passed so that it is turned into the line of travel of said work-sheet web.
11. The combination with a typewriting machine having a platen of means for guiding a fanfold work-sheet web to said platen, a carbon carrier movable on said machine toward and away from said platen comprising a rotary spool for holding superposed carbon sheets provided to be interleaved with the plies of said work-sheet web, means for directing said carbon sheets from said spool crosswise of the path of movement of said carrier so as to be interleaved with said plies, guiding means on said carbon carrier for directing said carbon sheets into the line of movement of said work-sheet web, means for movably securing said guiding means to said carbon carrier so that they can readily be moved from their working positions to facilitate the interleaving of said carbon sheets with said plies, and a member mounted so as to be moved into engagement with said rotary spool for locking said spool against rotation.
12. The combination with a typewriting machine having a platen of means for guiding a plurality of superposed work-sheets to said platen, a carbon carrier mounted for movement toward and away from said platen in the line of movement of said work-sheets,

rotary spools on said carrier for holding superposed carbon sheets provided to be interleaved with said work-sheets, means for guiding the carbon sheets crosswise of the path of movement of said carbon carrier and for separating the superposed sheets for interleaving with said work-sheets, guide members pivotally mounted on said carbon carrier arranged to turn and direct said carbon sheets along the line of movement of said work-sheets and a pin cooperating with each spool for positively locking it against rotation.

13. In a type-impressing machine having a platen over which the work-web travels, the combination with carbon-spools mounted at opposite sides of the path of travel of the incoming work-web, of swiveled diagonal carbon-directing flaps between which the plies of work-web are threaded between said spools, said diagonal flaps serving to alter the course of the transversely incoming carbons into correspondence with the direction of travel of the work-web; said diagonal flaps being swiveled to permit them to be swung to idle positions off from the work-web, and to be returned to working positions, one after another, between the plies of work web, in building up the composite web.

14. In a type-impressing machine having a platen over which a multiple-ply work-web travels, the combination with carbon-spools mounted at opposite sides of the path of travel of the incoming work-web, of vertically-spaced rods to separate and guide the transversely incoming carbons, and swiveled diagonal carbon-directing flaps between which the plies of the work-web are threaded between said spools, said diagonal flaps serving to alter the course of the transversely incoming carbons into correspondence with the direction of travel of the work-web; said flaps being swiveled to permit them to be swung to idle positions off from the work-web and to be returned to working positions, one after another, between the plies of the work-web in building up the composite web.

15. In a type-impressing machine having a platen over which a multiple-ply work-web travels, the combination with carbon-spools mounted at opposite sides of the path of travel of the incoming work-web, of swiveled angularly bent wires forming carbon-directing members between which the plies of the work-web are threaded between said spools, each of said wires including two branches, one branch arranged to extend diagonally across the work-web to alter the course of one of the transversely incoming carbons into correspondence with the direction of travel of the work-web, the other branch being bent at an angle from the diagonal branch to form a strut for said diagonal branch; said wires being swiveled to permit them to be swung to idle positions from off the work-web and

to be returned to working positions, one after another, between the plies in building up the composite web.

16. In a type-impressing machine having a platen over which a multiple-ply work-web travels, the combination with carbon-spools mounted at opposite sides of the path of travel of the incoming work-web, of vertically-spaced rods to separate and guide the transversely incoming carbons, and swiveled angularly bent wires forming carbon-directing members between which the plies of the work-web are threaded between said spools, each of said wires including two branches, one branch arranged to extend diagonally across the work-web to alter the course of one of the transversely incoming carbons into correspondence with the direction of travel of the work-web, the other branch being bent at an angle from the diagonal branch to form a strut for said diagonal branch; said wires being swiveled to permit them to be swung to idle positions from off the work-web and to be returned to working positions, one after another, between the plies in building up the composite web.

17. In a type-impressing machine having a platen over which a multiple-ply work-web travels, the combination with carbon-spools mounted at opposite sides of the path of travel of the incoming work-web, of swiveled diagonal carbon-directing flaps between which the plies of work-web are threaded between said spools, said diagonal flaps serving to alter the course of the transversely incoming carbons into correspondence with the direction of travel of the work-web, and means mounting said flaps for swiveling to permit them to be swung to idle positions off from the work-web and to be returned to working positions, one after another, between the plies of work-web in building up the composite web, said mounting means and flaps being arranged to permit easy removal and replacement of said flaps from and in said mounting means.

18. In a type-impressing machine having a platen over which a multiple-ply work-web travels, the combination with carbon-spools mounted at opposite sides of the path of travel of the incoming work-web, of swiveled angularly bent wires forming carbon-directing members between which the plies of the work-web are threaded between said spools, each of said wires including two branches, one branch arranged to extend diagonally across the work-web to alter the course of one of the transversely incoming carbons into correspondence with the direction of travel of the work-web, the other branch being bent at an angle from the diagonal branch to form a strut for said diagonal branch, and spaced-apart supports mounting said wires for swiveling to permit them to be swung to idle positions off from the work-web and to be

returned to working positions, one after another, between the plies of the work-web in building up the composite web, said supports and wires being arranged to permit easy removal and replacement of said wires from and in said supports.

In witness whereof, I have hereunto set my hand this 8th day of November, 1929.

DAVID W. RUBIDGE.
